UNITED STATES PATENT OFFICE.

WILLIAM J. KENNEDY, OF JERSEY CITY, NEW JERSEY.

FURNACE.

1,307,906.

Specification of Letters Patent. Patented June 24, 1919.

Application filed July 13, 1918. Serial No. 244,772.

To all whom it may concern:

Be it known that I, WILLIAM J. KENNEDY, a citizen of the United States, and a resident of Jersey City, in the county of Hudson and State of New Jersey, have invented a new and Improved Furnace, of which the following is a full, clear, and exact description.

This invention relates to furnaces and has for an object the provision of an improved construction which utilizes to a maximum extent the heating value of the fuel by causing an absorption of the heat and a transmission of the heat to a considerable medium.

Another object in view is to provide a heating furnace for heating small or large houses with steam or hot water with the parts so constructed and arranged that the water is quickly heated and substantially super-heated as it leaves the furnace so as to be supplied to the radiators at a desirable temperature.

A still further object of the invention is to provide a construction of furnace which will utilize fully the hot gases as they escape from the fire chamber for heating and super-heating the water or steam in the upper part of the furnace.

30 In the accompanying drawings:

Figure 1 is a front view of a furnace constructed according to the present invention.

Fig. 2 is a longitudinal vertical section 35 through the furnace shown in Fig. 1.

Fig. 3 is a transverse sectional view through Fig. 2 approximately on line 3—3.

Fig. 4 is a section through Fig. 1 on line 4—4.

40 Referring to the accompanying drawings by numerals 1 indicates an outer shell or casing which extends downwardly to the base 2, which base may be any desired material. The upper end of the casing or shell 1 is preferably rounded and is provided with a number of apertures normally filled with plugs 3. Arranged in the casing

45 1, but spaced therefrom is an inner casing or shell 4 of the same shape as the outer casing 1 except that it does not extend down to the foundation 2, but is bolted or otherwise secured to the ring 5, the securing bolts

extending through the casing 1 as shown in Fig. 2. This provides a water tight connection at this point as well as a supporting structure for the bottom part of the casing. By providing the inner and outer shell as just described is formed a water chamber 6 extending from the grate 7 to the extreme top of the furnace and entirely around the furnace except at the point occupied by the door 8. A return pipe 9 is connected to the casing 1 near the lower part thereof so as to discharge the return water into the furnace at a comparatively cool point. The grate 7 may be any desired kind of a grate as for instance a stationary grate and the ashes allowed to drop into the ash pit 10 from which they may be removed through door 11. In the upper part of the inner casing 4 is provided a number of tubular heating members 12 which are closed at the inner end and open at the outer end so that water from the chamber 6 may freely pass into the heating members 12 and leave therefrom. These heating members are preferably expanded in place similar to an ordinary tubular boiler, though they may be fastened in any desired way.

From Fig. 2 it will be seen that the tubular heating members 12 are in line with the plugs 3, which plugs are desired to be removed when any of the heating members 12 are to be renewed. It is, of course, understood that the openings closed by the various plugs 3 are sufficiently large to permit the tubes 12 to pass.

Arranged near the top of the boiler formed by the casings 1 and 4 and associate parts are a number of tubular smoke members 13 which are expanded in place or secured in any desired manner whereby the smoke and hot gases may not only freely pass between the various tubes 12 on the sides of the casing 1 and tubes 12 at the top, but may pass to the exterior casing 1 and maintain the exterior in a heated condition. A hood 14 surrounds the outer casing 1 on the upper part and down to a plate 15 which extends entirely around the outer casing 1 except at the point opposite door 8 where there is a recess provided. Above the plate 15 is what may be termed a smoke regulating plate 16, which is a ring and extends en-

tirely around the outer casing 1 and is provided with a number of apertures 17 through which the smoke passes from the chamber 18 into the chamber 19 formed of plates 15 and 16. A regulating damper is provided for each of the apertures 17, said dampers each having an arm 21 extending through the hood 14 so that the dampers may be properly moved and positioned to cause the smoke to move in the desired path. A smoke pipe 22 enters into the chamber 19 at 23, said smoke pipe being provided with a damper 24 if desired. In order to prevent the smoke and hot gases from moving to the point 23 along the shortest lines a division plate 25 extends from the top of the hood 14 to plate 16 between the respective openings 17 as shown in Fig. 3 whereby the smoke must pass into the various auxiliary chambers 18' and from thence downwardly into the chamber 19 and from thence into the pipe 22. In order to have a substantially equal amount of smoke passing through each of the chambers 18' a damper 20 farthest from the point 23 will be opened to the greatest extent and the others gradually less and less, and the damper at the point opposite the pipe will be opened to the least extent. In starting a fire all the dampers may be opened completely in order to provide a proper strong draft, but after the fire has been properly started the dampers may then be regulated as described, or in any other desired manner in order to secure a maximum heat from the hot gases and smoke as well as directly from the flame of the fire on the grate 7.

In the case of steam the hood 14 will cause the upper part of the casings 1 and 4 to be heated to an appreciable extent by the smoke and hot gases so that the steam in the upper part of the furnace will become somewhat superheated and thereby pass out of the discharge pipe 26 in the best possible condition. Where hot water is used for carrying the heat the same desirable result will be secured as the water will leave the furnace in the hottest condition possible with the given fire.

It will, of course, be evident that the furnace could be made large or small as desired and that any desired number of heating members 12 and 12' may be used as well as any desired number of smoke pipes 13.

In constructing the door 8 it is preferably formed to close a comparatively large opening 27 which ordinarily is left closed while the auxiliary door 28 is opened when supplying coal. When it is desired to stoke the fire the vertically swinging door 29 is opened and the stirring member inserted. When removing clinkers or other objectionable matter the door 8 is opened and as the top of the grate 7 is in line with the bot-

tom of the frame 30 in which the opening 27 is positioned the clinkers may be easily pulled out and the fire cleaned.

What I claim is:

1. A furnace comprising a body formed with a water chamber, means for supporting a fire in said body, a plurality of heat pipes extending through said water chamber to a point exterior of the body whereby the smoke and other burnt products of combustion may pass from the fire on the fire supporting means through said water chamber, a hood surrounding the upper part of said body into which the burnt products of combustion are discharged, a smoke pipe connected with said hood at substantially the lowest point, and a plurality of spaced dampers for regulating the draft from the hood and the smoke pipe.

2. A furnace of the character described comprising a heating body formed to heat water, said heating body having openings through which the smoke will pass, a hood arranged over the upper part of said body and into which the smoke is discharged, a plurality of vertically arranged partitions positioned in the hood, a ring arranged at the bottom of said partitions, said ring having an aperture between each partition, a damper for closing said apertures, means forming a chamber beneath said ring, and a smoke pipe connected with said chamber.

3. A furnace comprising a body formed with means for supporting a fire and a hollow section for heating water, said body being provided with a discharge passageway for the smoke and burnt products of combustion, a hood surrounding said body said hood being formed with a bottom, a ring arranged above said bottom whereby there is provided a chamber between the bottom and the ring, said ring being formed with a plurality of smoke outlets, a smoke pipe connected with said casing and opening into said chamber, a plurality of vertical division plates arranged in said hood extending from the top downward to said ring so as to divide the space inclosed by the hood into a plurality of compartments into which the smoke passes, there being a smoke outlet for each compartment, a damper for each of said smoke outlets in said ring, and means for moving said damper back and forth over said smoke outlets so as to control the passage of smoke and burnt products of combustion therethrough.

4. A furnace comprising a body formed with a water chamber, means for supporting a fire in said body, a plurality of heat pipes extending through said water chamber so that the products of combustion may pass to a point exteriorly of the water chamber, a hood surrounding the upper part of said body adapted to receive said

products of combustion, a plurality of division plates arranged in said hood, a bottom member connecting said hood with said body, a ring provided with a plurality of 5 openings spaced above said bottom whereby there is provided a chamber between the ring and the bottom, a shutter for each of

said openings, means connected with each of said shutters extending to a point exteriorly of the hood for moving the shutter so 10 as to open and close said openings, and a smoke discharge pipe connected with said chamber.

WILLIAM J. KENNEDY.
